[57] CLAIM

The ornamental design for a yoke for an exercise bicycle, as shown and described.

DESCRIPTION

FIG. 1 is a perspective view of a yoke for an exercise bicycle showing my new design;

FIG. 2 is a top plan view thereof;

FIG. 3 is a bottom plan view thereof;

FIG. 4 is a left side elevational view thereof, the side opposite being a mirror image;

FIG. 5 is a rear elevational view thereof; and,

FIG. 6 is a front elevational view thereof.

The broken line showing of FIG. 1 is for illustrative purposes only and forms no part of the claimed design.

FIG 2

FIG 3

FIG 5

FIG 6
